Primary Examiner — Marie D. Fast Horse(74) *Attorney, Agent, or Firm* — Bin Sun(57) **CLAIM**

The ornamental design for the computer mouse docking station, as shown and described.

DESCRIPTION

FIG. 1 is a top, front perspective view of a computer mouse docking station showing my new design.

FIG. 2 is a top elevation view of thereof.

FIG. 3 is a front elevation view thereof, the back side being a mirror image thereof; and,

FIG. 4 is a left elevation view thereof, the right side being a mirror image thereof.

The bottom of the computer mouse docking station is flat and unornamented.
